Fig. 12

FIG. 1 is a perspective view taken from the left front side of a door embodying my new design;

FIG. 2 is a rear view of the embodiment shown in FIG. 1;

FIG. 3 is a right side elevation of the embodiment shown in FIG. 1;

FIG. 4 is a top view of the embodiment shown in FIG. 2;

FIG. 5 is an enlarged section taken as indicated by the lines and arrows 5-5 in FIG. 3;

FIG. 6 is a perspective view taken from the left front side of another door embodying my new design;

FIG. 7 is a rear view of the door shown in FIG. 6;

FIG. 8 is a right side elevation of the door shown in FIG. 6;

FIG. 9 is a top view of the door shown in FIG. 7;

FIG. 10 is an enlarged section taken as indicated by the lines and arrows 10-10 in FIG. 8;

FIG. 11 is a perspective view taken from the left front side of another door embodying my new design;

FIG. 12 is a rear view of the embodiment shown in FIG. 11;

FIG. 13 is a right side elevation of the embodiment shown in FIG. 11;

FIG. 14 is a top view of the embodiment shown in FIG. 12; and

FIG. 15 is an enlarged section taken as indicated by the lines and arrows 15-15 in FIG. 13.

The shading employed does not connote actual appearance, but is an expedient to best illustrate the various embodiments.

I claim:

The ornamental design for a door, as shown and described.
